UNITED STATES PATENT OFFICE

104,244

DESIGN FOR A LIQUID DISPENSER

Joseph M. De Lacy, Chicago, Ill.

Application January 6, 1936, Serial No. 60,440

Term of patent 3½ years

To all whom it may concern:

Be it known that I, Joseph M. De Lacy, a citizen of the United States, residing at Chicago, in the county of Cook and State of Illinois, have invented a new, original, and ornamental Design for Liquid Dispenser, of which the following is a specification, reference being had to the accompanying drawing forming a part thereof.

Figures 2 and 3 are plan and front views respectively of the dispenser.

I claim:

The ornamental design for a liquid dispenser substantially as shown.

JOSEPH M. DE LACY.
